METHOD OF CEMENTITIOUSLY CASING
SUBMERGED PILINGHarry Gast, Los Angeles, and Frank W. Freeman,
Inglewood, Calif.

Application March 6, 1944, Serial No. 525,296

9 Claims. (Cl. 61—54)

This invention relates to a method of protecting and reinforcing submerged wood piling.

As is well known, submerged wood piling deteriorates above the formation into which it is driven and it becomes necessary either to protect and reinforce the weakened piling or replace it. It has been found that the most satisfactory way of protecting and reinforcing such piling has been to apply a protective casing of cementitious material to the exterior of the piling from the formation upwardly to a point above the water line. However, prior to our invention, no satisfactory method of applying an effective cementitious reinforcing casing to submerged wood piling has been produced.

Our invention has for its principal object the provision of an efficient method of expeditiously applying an effective reinforcing and protecting casing of cementitious material to submerged wood piling.

In carrying our invention into practice, we form a cementitious reinforced casing in successive steps directly on the piling adjacent its upper end and lower the casing downwardly as it is formed until the entire pile is encased from the formation upwardly.

Our invention is exemplified in the following description and illustrated by way of example in the accompanying drawings, in which:

Fig. 1 is a view of a pile protected and reinforced by a casing constructed in accordance with our present invention.

Fig. 2 is a view in elevation and in longitudinal section of the form employed in producing the sections of casing.

Fig. 3 is a view of the reinforcing means employed for each section of casing, and disclosing the manner in which it is arranged on the form.

Fig. 4 is a view in elevation and in section of the first completed section of the casing.

Fig. 5 is a cross-sectional view taken on line 5—5 of Fig. 4.

Fig. 6 is a similar view showing the first section of the casing lowered from the form so that the succeeding section may be produced.

Fig. 7 is a view similar to Fig. 6 showing the second section completed and joined to the first section.

Referring more particularly to the accompanying drawings, we have there illustrated the preferred manner of practicing our invention. In the drawings, 10 indicates a wharf or quay supported on wood piling 11 driven into the formation 12. By way of example, we indicate a water line at 14 and a mud line at 15. We intend that a

unitary reinforced cementitious casing 16 be placed over the pile 11 between the formation 12 and a point a distance above the water line 14 to protect and reinforce the pile 11.

To accomplish this we construct a cylindrical form 17 concentrically around the pile above the water line 14. This form 17 is preferably formed of sheet metal, although other materials may be used, and it is of a diameter approximately four inches greater than the diameter of the pile. The lower end of the cylindrical form 17 may be slightly less in diameter than its upper end to provide draft sufficient to enable a cementitious tubular casing section formed thereon to be more easily lowered off of the form 17. The form 17 may be suspended from the wharf by suspension cables or chains 18, or it may be held in place in any other desired manner. Spacing cleats 19 are disposed between the interior of the form 17 and the pile 11 to maintain the form concentrically of the pile.

To construct the cementitious casing about the pile we propose to form the casing 16 in tubular sections somewhat less in length than the length 25 of the form 17. We prefer that the length of the form be six feet, although other lengths may be used. Each tubular section 16a is formed on the form 17 and then lowered with respect to the form 17 to a point where the upper end of the tubular 30 section is telescoped over the lower extremity of the form, as illustrated in the drawings. This is so that the upper end of the section 16a so formed may be joined to the succeeding tubular section constructed on the form 17.

Each tubular section 16a of the casing is reinforced by a steel reinforcing fabric 20 embedded therein during the formation thereof. The reinforcing element 20 of each tubular section 16a is joined end to end with the reinforcing element 20 40 of the preceding section by wire tying or otherwise. Prior to the application of the cementitious material to form a tubular section 16a, a section of the reinforcing material is wrapped concentrically over the form 17 to a diameter 45 somewhat (say two inches) greater than the external diameter of the form 17, thus forming the reinforcing element 20. Thereafter a cementitious mixture is applied over the form by the concrete gun method commonly known in the trade 50 as "Gunite," so as to form a tubular section 16a having a wall approximately two inches thick.

The method of applying the cementitious mixture, as before stated, is commonly known as the "Gunite" method and we prefer to employ such 55 method, although various other methods of ap-

plying the cementitious mixture to the form in constructing a tubular section 16a may be employed if desired.

The upper end of each tubular section 16a of the cementitious material is frusto-conical and extends short of the upper extremity of its reinforcing fabric cylinder 20. This is so that when the succeeding tubular section is fabricated, the lower end of its reinforcing element 20 may be joined by wire tying or otherwise to the upper end of the reinforcing element 20 of the preceding section. The lower end of each succeeding tubular section 16a is formed directly over the frusto-conical end of the preceding section so as to become integrally joined therewith. Each tubular section 16a when formed is, of course, permitted to remain on the form 17 a sufficient length of time to become form-sustaining.

To lower the cementitious casing 16 step by step as the tubular sections 16a thereof are formed, the reinforcing cylinder or element 20 of the first section of the casing 16 is fitted with suspension bars or eyes 21 at its upper end and spacer guides 22 at its lower end. The latter act to maintain the lower extremity of the cementitious casing 16 concentric with respect to the pile 11. The suspension bars or eyes 21 are attached to the lower ends of chains or cables 23 which are led to a point above the pile or wharf to enable suspension of the cementitious casing 16 and the controlled lowering thereof as the sections of it are completed.

The tubular sections 16a are successively formed until the cementitious casing rests on the formation 12 into which the pile is driven. Obviously, the weight of the cementitious casing 16 is sufficient to sink the same through any mud strata overlying the solid formation into which the pile is driven.

When the casing has been thus formed and positioned in place, an annular spacing of approximately two inches or more will separate the inner periphery of the casing 16 from the outer periphery of the pile. This space is filled with sand cement grout in any preferred manner, thus forming a reinforced cementitious casing about the pile of approximately four inches thick and extending from the formation 12 upwardly to any desired point above the water line 14.

After grouting the casing 16, the form 17 is removed from the pile and a cementitious casing cap 24 is formed directly on the pile and joined with the upper end of the last tubular section of the cementitious casing 16.

Obviously, by our improved method, weakened and deteriorated submerged piling may be efficiently protected and reinforced by a tightly gripping, surrounding casing of reinforced cementitious material from the formation into which the pile is driven to any desired point above the water line. Further, it is apparent that such cementitious casing may be applied to a pile at a comparatively low cost.

While we have described our invention in detail and the specific steps for practicing it, it is to be understood that various changes may be made in its construction by those skilled in the art without departing from the spirit of the invention as defined in the appended claims.

Having thus described our invention, what we claim and desire to secure by Letters Patent is:

1. A method of applying a cementitious casing to piling which comprises successively forming tubular sections of cementitious casing directly

on the piling adjacent its upper end and of an internal diameter greater than the external diameter of the piling, and lowering said casing step by step on the piling as said casing is formed.

5 2. A method of applying a cementitious casing to piling which comprises successively forming tubular sections of cementitious casing directly on the piling adjacent its upper end and of an internal diameter greater than the external diameter of the piling, lowering said casing step by step on the piling as said casing is formed, and filling the annular space between the casing and the piling with cementitious material after said casing has been completed.

10 3. A method of applying a cementitious casing to piling which comprises successively forming reinforced tubular sections of cementitious material directly on the piling adjacent its upper end and of an internal diameter greater than the external diameter of the piling, connecting each section as it is formed to the preceding section, maintaining the casing so formed suspended on the piling as the sections are formed, and lowering the casing step by step on the piling as the sections are formed until the bottom of the casing rests on the formation into which the piling is driven.

25 4. A method of applying a cementitious casing to piling which comprises successively forming reinforced tubular sections of cementitious material directly on the piling adjacent its upper end and of an internal diameter greater than the external diameter of the piling, connecting each section as it is formed to the preceding section, 30 maintaining the casing so formed suspended on the piling as the sections are formed, lowering the casing step by step on the piling as the sections are formed until the bottom of the casing rests on the formation onto which the piling is driven, and grouting the annular space between the casing and the piling after the casing has been completed.

35 5. A method of applying a cementitious casing to piling which comprises fitting a form to the piling adjacent its upper end, successively forming tubular cementitious casing sections on said form, maintaining the casing so formed suspended on the piling, lowering the casing on the piling as each section is completed to remove the last completed section from the form, and connecting the lower end of each section while forming the same to the upper end of the preceding section.

40 6. A method of applying a cementitious casing to piling which comprises fitting a form to the piling adjacent its upper end, successively forming tubular cementitious casing sections on said form, maintaining the casing so formed suspended on the piling, lowering the casing on the piling as each section is completed to remove the last completed section from the form, connecting the lower end of each section while forming the same to the upper end of the preceding section, and filling the space intermediate the casing and the piling with cementitious material after the casing has been completed.

45 7. A method of applying a cementitious casing to piling which comprises fitting a form to the piling adjacent its upper end, successively forming tubular cementitious casing sections on said form by spraying a cementitious mixture on said form, lowering the casing the length of a section after the formation of each section until the casing 50 extends to the formation into which the pil-

ing is driven, and then filling the annular space between the casing and the piling with cementitious material.

8. A method of applying a cementitious casing to piling which comprises fitting a form to the piling adjacent its upper end, successively forming reinforced tubular cementitious casing sections on said form by successively arranging a reinforcing element over the form and spraying a cementitious mixture on said form embedding said reinforcing element, lowering each section when formed from the form until the casing so constructed rests on the formation into which the piling is driven, then filling the annular space between the casing and the piling with cementitious material.

10

15

9. A method of applying a cementitious casing to piling which comprises fitting a form to the piling adjacent its upper end, successively forming reinforced tubular cementitious casing sections on said form by successively arranging a reinforcing element over the form and spraying a cementitious mixture on said form embedding said reinforcing element, lowering each section of casing after it is formed from the form, connecting each reinforcing element as it is arranged on the form to the reinforcing element of the preceding section, and joining each section as it is formed to the preceding section.
